WINDOW-RAISING AND LOCK-RETRACTING
MEANS

Carl F. H. Krug, Cincinnati, Ohio

Application March 19, 1938, Serial No. 196,830

5 Claims. (Cl. 74—547)

This invention relates to devices for raising windows and particularly windows of automobiles, an object being to provide an improved construction which may be readily actuated to secure the desired result but which when not in use will be out of the way and substantially flush with the door.

Another object of the invention is to provide an improved construction which is normally embedded in the door but which may be swung outwardly and then manipulated to raise the window of the automobile.

An additional and more specific object of the invention is to provide an automobile window-raising structure which includes a manipulating handle that is normally embedded in the door but which may be caused to move a short distance therefrom through the action of a lever mechanism, or may be grasped and swung outwardly, after which it is adapted to be manipulated to cause the window to be raised.

In the accompanying drawing—

Fig. 1 is an inside elevation of an automobile door with an embodiment of the invention applied thereto, said embodiment including means for actuating the window-raising mechanism.

Fig. 2 is an enlarged elevation of the hand-actuating mechanism for raising the window shown in Fig. 1;

Fig. 3 is a sectional view through Fig. 2 approximately on the line 3—3;

Fig. 4 is a view similar to the right-hand end of Fig. 3 but with the handle swung to an open or functioning position.

Referring to the accompanying drawing by numerals, 5 indicates an automobile door of any desired kind provided with a suitable window 2, a locking mechanism 3, and a window-raising mechanism 4, which may be of any desired construction now in common use.

The present invention is the construction or provision of means for actuating the mechanism 4 which is the usual mechanism for raising and lowering a window. This means, as illustrated in Figs. 1 to 4 inclusive is substantially embedded in the door 1 so as to eliminate any substantial protrusion of any of the parts. In the actuating mechanism now found in the average automobile, cranks are used and the crank knobs as well as the cranks extend an appreciable distance inwardly so that often the hand or clothes of a person are caught thereby. In the present instance the means for actuating the window-raising mechanism is normally embedded in the

door and, therefore, forms no objectionable protrusion.

Referring more particularly to Figs. 2 and 3, an actuating mechanism is provided for the window-raising mechanism. As indicated in Figs. 5 and 3, 5 indicates a door of any desired structure and to this door a retaining plate 6 is secured by screws or other suitable means. On top of plate 6 is provided what may be termed a base plate 7 and the various parts of the device are secured to the base plate, which in turn is secured by screws or other means to the plate 6. The base plate 7 is provided with an elongated socket 8 in which a handle 9 normally rests, as shown in Fig. 3. This handle is preferably a flat piece of metal and has secured thereto a knob 8 which may be rigid or may rotate as preferred. A retaining plate 10 is held by suitable screws 11 to plate 7 and has a knob housing 12 welded or otherwise rigidly secured thereto. This housing is preferably sheet metal and extends into the door but not therethrough. It will be noted that plate 10 is provided with an aperture in line with the bore of housing 12 so that the knob 8 may readily fit into its nested position, as shown in Fig. 3. At the end of handle 9 opposite knob 8, there is provided a bifurcated structure 13 having projecting ends 14 and 15 resting on a bearing plate 16. The shaft 17 which actuates the mechanism 4 extends through the bearing plate 16 and through the bifurcated end 13 to which it is secured by a pivotal pin 18. The bearing member 16 is disk-shaped and rests in a bearing casing 19 which is secured by screws 20 to the base plate 7, as shown in Fig. 3. A 35 tubular extension 21 is secured by welding or otherwise to member 19 so as to surround and protect a spring 22, which at one end presses against the bearing member 16 and at the other end against an abutment 23 held in place by a pin 24. By reason of this spring there is a continuous tendency or strain on pin 18 to hold the handle in its closed or nested position.

When it is desired to use the handle it is swung over to the position shown in Fig. 4 and as it is swung the rounded ends 14' and 15' press on the bearing member 16 and, consequently, pull the shaft 17 outwardly against the action of spring 22 during the outward swinging movement of the handle. It is to be noted that the central 50 tongue portion 25 and adjacent parts of the bearing 16 are thicker than the remaining parts, as shown in Fig. 4, so that when the handle 9 is moved over to its fully functioning position it will rest on portion 25 and therefore be above 55

or outward from the base plate 7. The shaft 17 is provided with diametrically opposite notches or depressions 26 which are adapted to receive a ball or catch 27 which is pressed by a spring 28. 5 As the catch 27 is rounded it may be readily forced out of the notches 26 against the action of spring 28, but unless some force is used the parts will remain positively in the position shown in Fig. 4 or positively in the position shown in Fig. 3. 10 As the surface of the device is almost smooth throughout, the handle 9 cannot be grasped when it is folded as shown in Fig. 3. In view of this fact there is provided a push button 29 which extends through a suitable aperture 30 in handle 15 9 and into a housing 31 welded or otherwise rigidly secured to the plate 10. If desired, a guiding ring 32 could be secured to the housing 31 in order to properly center and hold slidably the button 29 in its functioning position. A spring 20 33 acts at one end on the button 29 and at the other end on the housing 31 for normally holding the button in the position shown in Fig. 3. The shaft 34 is preferably rigidly secured to the button 29 and loosely extends through the end or 25 base of housing 31 where it carries a pin 35 extending through a slot 36 in the lever 37. The lever 37 is pivotally mounted at 38 to a suitable bracket 39 secured to housing 31. This lever is also pivotally connected at 40 with a push rod 30 41 loosely extending through a cone-shaped aperture 42 in plate 10. By reason of this construction, whenever button 29 is pushed the handle 9 with knob 8 will move outwardly to the dotted position shown in Fig. 3 and then the handle is 35 grasped by a person and moved to the second dotted position shown in Fig. 3, and finally over to the position shown in Fig. 4. When the parts are in the position shown in Fig. 4, the knob 8 may be grasped and the shaft 17 rotated for 40 actuating the mechanism 4 to raise the window 2. After the window has been raised or lowered as desired, knob 8 is swung over toward the dotted position shown in Fig. 3 and then released. The spring 22 will finish the movement so that 45 eventually the parts will be properly nested, as shown in Figs. 2 and 3. When in this position all of the parts will be out of the way and there will be no objectionable protuberances within the car.

50 I claim:

1. A control handle for a reciprocating and rotating shaft comprising a handle member pivotally connected at one end to one end of said shaft, said handle member having a bifurcated portion straddling said shaft with the ends thereof projecting beyond said shaft in one direction and the remaining part of the handle member projecting from said shaft in the opposite direction, a knob connected with said remaining part 55 of said handle member, and a spring acting on said shaft tending to pull the handle member in one direction whereby when said handle member

is swung on said bifurcated portion the shaft will be moved longitudinally a predetermined distance against the action of said spring, said handle member being adapted to be swung through an arc of approximately 180° whereby 5 it may be rotated for rotating said shaft.

2. In a device of the character described, a control handle for a shaft having a bifurcated end, said shaft extending through said bifurcated end, a pivotal pin for pivotally connecting said handle with said shaft, a bearing member through which said shaft extends, said bearing member having a raised portion whereby when said handle is swung on said bifurcated end, said shaft will be moved longitudinally, said handle being adapted 10 to be moved through an arc of approximately 180° and rest on said raised portion, and a spring acting on said bearing member and on said shaft for resiliently holding said handle in either of its extreme positions, said handle when pressing on said raised portion being adapted to be moved 15 to rotate said shaft.

3. In a device of the character described, a control handle for a shaft provided with a knob, means for pivotally mounting one end of said handle onto said shaft, a base plate provided with a recess for receiving said handle when the same is nested, a housing carried by said base plate for receiving said knob, said handle being adapted to be swung to an arc of approximately 180° 25 from a nested position to an open or functioning position, and a spring acting on said shaft and said handle for resiliently holding the handle in either of its extreme positions, said handle when swung to the functioning position being adapted 30 to be rotated for rotating said shaft.

4. In a device of the character described, a control handle for a rotatable shaft provided with a knob, means for pivotally connecting said handle at one end to said shaft, means for normally 40 embedding said handle, said handle being adapted to be swung from an embedded position to an open functioning position, said swinging movement being through approximately 180°, and a spring for holding said handle in either of its 45 extreme positions.

5. In a device of the character described, a control handle for a rotatable shaft, a base plate provided with a recess for normally permitting said handle to be embedded therein, said handle having a bifurcated end arranged so that one end of said shaft will project from said end, a pivotal pin for pivotally connecting said shaft to said bifurcated end so that the bifurcations will project beyond the shaft whereby when said handle is swung from one position to another through an arc of 180° said shaft will be pulled longitudinally and then moved back to its former position and a spring acting on said shaft for resiliently holding said handle in either of its extreme positions. 60
